UNITED STATES PATENT OFFICE.

CARL P. ASTROM, OF EAST ORANGE, NEW JERSEY, ASSIGNOR TO M. H. TREADWELL COMPANY, OF NEW YORK, N. Y., A CORPORATION OF NEW YORK.

HOT-METAL CONTAINER.

Application filed October 31, 1925. Serial No. 65,921.

This invention relates to hot metal containers or ladles and has for its object to provide such a container which has reduced heat radiation losses, lessened operating costs, reduction in weight of material required for the container, and which requires less power to tilt.

Containers for hot metal heretofore used have been of various shapes, some cylindrical about either axis, some rounded at the ends or at the bottom. These containers are generally lined with a heat resistant brick of some sort, but even the best of linings cannot withstand the effect of the hot metal and need replacing. Where the container is of nonuniform curvature in some parts the lining replacement cost is high due to the expense of using specially shaped bricks, or else the labor cost is high due to the necessity of carefully fitting all bricks. Even though the contour of a container be uniform curvature in most of its length, as for example, with a cylindrical container, nevertheless the ends of such cylindrical container require bricks to be fit in place differently.

According to this invention a spherical container is mounted on trunnions and lined with bricks which are all alike and shaped to engage and be wedged in place. The lining of a pouring spout cooperates with the bricks adjacent to it and retains the entire brick lining wedged in place.

The single figure of the drawing in the right half indicates a section through the container and in the left half illustrates the outside view.

The spherical container 10 is provided with a pouring spout 11 and is mounted on trunnions 12 for tilting.

The container and plurality of bricks 13 all of the same shape have their sides 14 uniformly tapered radially, the inner surfaces 15 of these bricks are curved in both directions about the center of the ladle, and the outer surfaces 16 are similarly and concentrically curved. Between the metal shell 18 and the brick lining 13 is a backing 17 of clay and ganister. The metal plates forming the container shell are shaped as illustrated in the left portion of the drawing, and are secured together by rivets 19, or otherwise. The metal pouring spouts 21 has a cementitious lining 20 also of clay and ganister. The lining 20 engages the side

faces of the adjacent bricks and prevents movement of the bricks towards the axis of the spout, thus serving to retain all of the bricks 13 wedged in position.

A container which is spherical in shape both above and below the trunnions and around the pouring spout is of the most efficient shape and provides a minimum radiation surface by comparison with the capacity of the container. The spherical ladle illustrated also enables a minimum weight of material to be used in the construction of the ladle for a given size. The wear on hot metal containers is very substantial, and all such containers require relining from time to time. With the lining composed of bricks all of the same shape, arranged to wedge and fit together the labor involved in replacing of linings is substantially reduced. Another advantage of the ladle of the type illustrated is the lessened effort required to tilt since it is substantially balanced in all positions and there is no lifting or raising of the center of gravity, in pouring, as is necessary when the container is not shaped like a solid of revolution about the trunnion axis. A sphere is the most efficient shape of solid to reduce heat radiation to a minimum since the surface is a minimum for the internal capacity. Having the bricks of the lining all alike and with radially tapered side faces does away with the necessity of any specially shaped bricks in some part of the container and not only makes replacement easier but more securely retains the bricks in position. The term spherical as used in the claims is not necessarily limited to a precise or geometric sphere, but rather indicates shapes which are substantially spherical and capable of being used to produce the new results of this invention.

I claim—

1. The combination with a hot metal container of spherical shape, of a plurality of similar bricks lining substantially the entire interior of the same and shaped for wedging cooperation with adjacent bricks.

2. The combination with a hot metal container of spherical shape, of a plurality of similar bricks lining substantially the entire interior of the same, each of said bricks having uniformly tapered and radial sides, the inner and outer surfaces of each of said bricks being spherical and concentric.

3. A spherical container having a plural-

ity of similar bricks lining substantially the entire interior of the same, the side faces of said bricks being uniformly radial and tapered, a pouring spout and a lining for said spout, said lining engaging the adjacent bricks to retain all of them in position.

4. A spherical container having a metal shell, a plurality of similar bricks lining the same, the faces of said bricks being uniformly tapered and radially disposed, a backing of clay and ganister between said shell and

bricks, a pouring spout, trunnions extending from substantially the center of said container shell, the lining of said spout retaining adjacent bricks in position, and the container being spherical above as well as below said trunnions. ¹⁵

Signed at New York, in the county of New York and State of New York, this 29th day of October, A. D. 1925.

CARL P. ASTROM.
